FLAT-WORK IRONER ROLL COVER

Samuel Lewis Morgan, Decatur, Ga., assignor to American Associated Companies, Atlanta, Ga., a corporation of Georgia

Application March 10, 1953, Serial No. 341,421

6 Claims. (Cl. 29—128)

This invention relates to improvements in flat-work ironers of the type provided with a plurality of ironing rolls adapted to rotate in complementary arcuate or concave seats in the upper surfaces of a plurality of steam chests for ironing flat-work as it is caused to move between the chest and rolls, but the invention is more particularly directed to an insulated aluminum cover for the roll and means permanently attached to the roll coating with complementary means carried by the cover for detachably securing the cover to the roll.

In connection with the flat-work ironers of the above character, the respective rolls are provided with a covering of padding material, which in turn is covered with duck or treated fabric which constitutes the ironing surface of the roll and which presents many disadvantages, among which may be noted: that such cover material is stiff and when wrapped around the roll with the trailing end free, in operation, the latter will fold over and crease causing the cover to split, thereby not only damaging the cover but giving a rough finish to the linen. This type of cover also permits heat to penetrate through the pad and to the roll, tending to burn up the pad and effecting a loss of heat, which increases the operation cost and slows down production; therefore, the principal object of this invention is the provision of an aluminum cover having an insulated surface next to the pad and roll which reflects heat therefrom, thereby tending to preserve the pad and such structure, increasing the life of the cover, and giving a smooth finish to the ironed material.

The covers heretofore in use have been secured to the roll at one end by gluing, which requires considerable time and effort to remove upon wearing out of the cover or because of damage thereto, requiring replacement with a new cover. Also, at times the gluing permits the covers to slip, which requires their replacement, and in order to replace such cover, a complete shut-down of the iron for a considerable time is necessary. Therefore, a further important object of this invention is the provision of a positive cover-attaching means mounted permanently on the rolls, and provided with anchoring means engageable with complementary means carried by the end of the aluminum cover, thereby enabling the cover to be removed and replaced in a few minutes.

In an ironing machine of this type employing a plurality of ironing rolls, at a point where the dampened and cold flat-work or linen enters between the heated chest, and the padded rolls, the initial rolls in operation are continuously wet and in a short time become compressed and also cease to absorb the moisture, and if the moisture is allowed to remain in the flat-work it causes a rough-dry finish. Therefore, another important object of this invention is the provision of perforations in the aluminum covers of the initial roll or rolls, depending upon the number of rolls in the particular machine, which perforations allow the moisture to pass into the underlying pad and dry out, whereby a smooth finish is imparted to the material being ironed.

A still further object of this invention is the provision

2

of a novel cover-attaching means and an insulated thin flexible aluminum cover that will go once around to completely cover the roll, but the free end of which will remain in place and impart a smooth finish to the ironed material.

Another important object of this invention is the provision of a covering assembly for flat-work ironer rolls comprising an envelope pad, a flexible metal cover for the pad, and interlocking means in connection with the roll and metal cover for detachably securing the cover in operative position about the roll.

With these and other objects in view, which will become apparent as the description proceeds, the invention resides in the construction, combination and arrangement of parts, hereinafter more fully described and claimed, and illustrated in the accompanying drawings, in which like reference characters indicate like parts throughout the several figures, of which:

Fig. 1 is a perspective view of a type of ironing machine, known as a flat-work ironer, the rolls of which are equipped with covers embodying my invention.

Fig. 2 is a detailed perspective view of a roll as shown in Fig. 1, and provided with my improved cover and means of attachment, with parts broken away progressively, to show the underlying pad and cover-fastening means.

Fig. 3 is a cross-sectioned elevation on an enlarged scale, taken on line 3—3 of Fig. 2, looking in the direction of the arrows.

Fig. 4 is a vertical transverse fragmentary sectional view of the multiple roll flat-work ironer, shown in Fig. 1, two rolls only being shown.

Fig. 5 is a detailed perspective view of my improved insulated aluminum roll cover indicated in Fig. 2.

Fig. 6 is a detailed perspective view as shown in Fig. 5 and showing the cover as perforated.

Fig. 7 is a transverse sectional view on line 7—7 of Fig. 5, looking in the direction of the arrows and showing the insulated under surface.

While my invention has been shown and described in connection with a mangle or flatwork ironers, it is adaptable with slight modification for use in connection with all types of ironers, such as chest, cylinder, combination chest and cylinder type, and home ironing machine.

In the illustrated embodiment characterizing this invention, there is shown generally, a mangle or flatwork ironer A embodying any desired number of ironing rolls B, in the present instance there being six of such rolls, by way of example.

The ironer A may have any desired number of rolls B, such as are indicated as 1, 2, 3, 4, 5 and 6, and which respectively are journaled at their opposite ends in bearings mounted on the oppositely disposed side plates 7. The rolls B rotate in concave seats 8 (Fig. 4) formed in the upper surfaces of the respective steam chests 9 located in the bottom portion of the machine A, and which effect heating of the respective covers C enveloping the rollers B, as and for a purpose directly more fully appearing. These rolls may be in excess of five feet long and diameter of a foot or more. Heretofore it has been difficult to attach and remove covers from the rolls, which are usually attached by gluing and when they become worn or damaged, usually it has been necessary to shut down the machine for a considerable period, and even then, it has been difficult to readily clean a roll in order to apply a new cover.

In order to effect a saving in time and effort in removing and replacing a worn or damaged cover C, an elongated anchoring and cover-fastening member D is mounted on each of the rolls B, which member D extends throughout the length of each roll, said member D comprising a substantially flat base flange portion 10 secured

to the outer surface of the roll by screws 11. The flange 10 is formed at its inner edge with a vertical upstanding web portion 12 terminating in a lateral flange portion 13, which extends in a direction opposite to the rotational direction of the roll, and which flange is vertically spaced from the surface of the roll. The flange portion 13 is formed with pairs of slits cut in its free edge extending substantially half-way through the flange, alternate resulting cut-out portions being upwardly and forwardly bent over the remaining portion of the flange forming the equi-spaced roll cover attaching hook members 14.

Mounted on each of the rolls B is a pad E of cotton, asbestos, felt or the like, with its forward end engageable beneath the flange 13 and abutting the vertical web 12, and its other end engaging the opposite side of the web 12. The forward edge of the pad is secured to member D by two or more substantially V-shaped wire fastening members 17 extending through spaced openings 18 in the web 12 preferably beneath the hook members 14 (Figs. 2 and 3), said members 17 terminating at their free ends in pointed upstanding hook points 19 engageable in the under surface of the pad to maintain said pad in operative and secured position about the roll.

The cover C is made of thin flexible aluminum and is formed along its fastening edge with a series of equi-spaced openings 15, corresponding to the number of anchoring members 14 over which said openings are adapted to engage and positively attach said cover to the roll B, which cover is adapted to extend once around the roll with the trailing end 16 overlappingly extending beyond the member D in a direction opposite to the rotational direction of the roll B (Fig. 2).

The cover C is provided on its under surface with a relatively thin asbestos insulating coating or covering F secured by a heat resistant adhesive. This aluminum cover while flexible will retain its shape about the roll and the trailing edge will not flat as do the covers now in use, and therefore will not fold over and crease, giving a rough finish, but will give a smooth finish to the ironed material. This cover being aluminum and insulated will reflect heat from the padded roll, thereby increasing the heat of the roll and preserving the life of the pad by directing heat therefrom, and said aluminum covers are not easily damaged by grommets in towels or other articles, such as buttons and the like, not only effecting a saving in operational cost, but adapted to last much longer and at the same time give a smooth finish to the ironed material.

The machine as illustrated in Fig. 1, is a six-roll, 120-inch ironer. While any size machine, employing different sized rolls, can be used in accordance with desired operating requirements, in the present instance, the six-roll machine is used for purposes of description. For preventing the imparting of a rough-dry finish to flatwork being ironed, which type of finish is found to be caused by accumulations of moisture on the covers C by engagement of the covers with damp and cold work being ironed, the covers C for the first three rolls, 1, 2, and 3 are provided, substantially throughout their areas, with a plurality of small perforations 20, the advantage of which is to allow excess moisture to enter into the moisture-absorbent pad E and dry out, which obviates the aforesaid rough-dry finish to the ironed flatwork. The last three rolls, 4, 5, and 6 insure a smooth finish.

It might be well to state that on a four-roll iron, two covers would be perforated and two solid, on an eight-roll iron, three covers are perforated and five solid, and on a two-roll iron, one cover would be perforated and one solid.

If desired, the surface of the aluminum cover may be provided with a wear-resisting coating, which is conveniently applied by an anodic treatment of the aluminum in a suitable electrolytic bath, it being found that the coating produced by the procedure described in Patent

No. 1,869,058, issued July 26, 1932 is suitable for prolonging the life of the aluminum cover.

From the above, it will be apparent that I have provided a novel roll cover and attaching assembly comprising a cover attaching structure permanently attached to each padded roll and a complementary attaching means formed in the aluminum roll cover, whereby a cover may be changed in a few minutes easily and quickly, thereby effecting a saving in machine stoppage, said insulated aluminum cover being adapted to permit the escape of moisture when required, and provides a smooth solid surface adapted to preserve the life of the pad and while preventing damage to the pad by a wasting of heat, thereby cutting down production cost, and at the same time being adapted to withstand hard and continued usage and to impart a desired smooth finish. The permanent attaching means being readily mountable on the roll and such features together with the readily attachable and detachable cover, are simple in construction, manufac-turable at a minimum cost and efficient for the purpose intended.

Although in practice I have found that the form of my invention illustrated in the accompanying drawings and referred to in the above description as the preferred embodiment, is the most efficient and practical; yet realizing that conditions concurrent with the adoption of my invention will necessarily vary, I desire to emphasize that various minor changes in details of construction, proportion and arrangement of parts, may be resorted to within the scope of the appended claims without departing from or sacrificing any of the principles of this invention.

Having thus described my invention, what I desire protected by Letters Patent is as set forth in the following claims:

35. 1. In an ironing machine for ironing flatwork, an ironing roll assembly which comprises an ironing roll, a moisture-absorbent pad carried by the roll and enveloping the roll, attaching means mounted on the roll and permanently secured to the roll, means connected to the attaching means coacting with the pad for removably securing the pad to the roll, a heat-reflecting cylindrical metallic cover sheet carried by the pad and enveloping the pad, and means adjacent to an end of the metallic cover sheet receiving complementary means on the said attaching means for securing the cover sheet to the pad while enabling the cover sheet to be removed and replaced readily, the said cover sheet having a smooth outer surface for engagement with work being ironed.

2. In an ironing machine for ironing flatwork, an ironing roll assembly, which comprises an ironing roll, a moisture-absorbent pad carried by the roll and enveloping the roll, elongated attaching means mounted on the roll substantially coincident with the length of the roll, means permanently securing the attaching means to the roll, spaced means on the attaching means coacting with the pad for removably securing the pad to the roll, a heat-reflecting metallic cylindrical cover sheet carried by the pad and having an outer surface for engaging work to be ironed and an inner surface, a layer of heat-insulating material secured to the inner surface of the cover sheet substantially coextensive therewith and intermediate the said pad and cover sheet, and means at an end of the said cover sheet engaging the means on the said attaching means for securing the cover sheet to the pad while enabling ready removal and replacement of the cover sheet relative to the pad.

3. In an ironing machine for ironing flatwork, an ironing roll assembly which comprises an ironing roll, a moisture-absorbent pad mounted on the roll and enveloping the roll, attaching means mounted on the roll and permanently secured directly to the roll and including spaced means coacting with the pad for removably securing the pad to the roll, a heat-reflecting cylindrical metallic cover sheet carried by the pad and enveloping the pad, and means on an end of the cover sheet engaging

the complementary means on the said attaching means for securing the cover sheet to the pad while enabling ready removal and replacement of the cover sheet relative to the pad, the cover sheet having a multiplicity of through-holes enabling transfer of moisture from damp work being ironed into the pad, the said cover sheet presenting a smooth outer ironing surface to the work being ironed.

4. In an ironing machine, an ironing roll assembly as claimed in claim 1, wherein the cylindrical cover sheet is a relatively thin flexible aluminum sheet having an anchoring end provided with means engaging with the complementary means on the attaching means, the said cover sheet extending only once around the pad and completely enveloping the pad, and having a free end opposite to the anchoring end, the said free end of the sheet overlappingly extending beyond the attaching means on the roll in counterdirection to rotational direction of the roll assembly.

5. The construction of claim 4 wherein the aluminum cover sheet is coated with a continuous anodized coating composed principally of aluminum oxide.

6. In an ironing machine, an ironing roll assembly as claimed in claim 1 wherein the attaching means mounted on the roll comprises a curved base secured directly and permanently to the roll and having an inner edge and an outer edge, the said inner edge being extended into an upstanding web portion terminating in a lateral flange portion, extending in a direction opposite to that of said base, the said flange being vertically spaced from the roll and having spaced slits therein dividing the flange into sections, alternate sections of the flange being bent upwardly and forwardly defining attaching hook members, the said upstanding web portion having spaced openings beneath the said hook members, and substantially V-shaped with fastening members extending through the said spaced openings and having free ends terminating in upstanding hook points, the said pad extending once-around the roll and having a leading end engaging the said up-

standing web portion of the attaching means and overlying the outer edge of the base of the attaching means, the pad having a trailing end opposite to the leading end and positioned between an opposite side of the said web portion and the said lateral flange portion of the attaching means, the said upstanding hook points of the V-shaped fastening members entering underside portions of the pad adjacent to its trailing end for maintaining the pad in operative and secured position about the roll, the said cover sheet overlying the pad and having a fastening end provided with a series of openings corresponding to the attaching hook members of the attaching means and receiving the hook members, the cover sheet extending once-around the pad and completely enclosing the pad and having a free trailing end opposite to the fastening end overlappingly extending beyond the attaching means and the hook members thereof in direction counter to rotational direction of the roll.
